UNITED STATES PATENT OFFICE

149,887

DESIGN FOR A BUILDING

Anton Kratochvil, Racine, Wis.

Application July 10, 1946, Serial No. 131,457

Term of patent 3½ years

(Cl. D13—1)

To all whom it may concern:

Be it known that I, Anton Kratochvil, a citizen of the United States, residing at Racine, in the county of Racine and State of Wisconsin, have invented a new, original, and ornamental Design for a Building, of which the following is a specification, reference being had to the accompanying drawing, forming part thereof.

In the drawing:

Fig. 1 is a perspective view of a building, showing my new design;

Fig. 2 is a top plan view thereof;

Fig. 3 is a side elevational view, looking at one of the gables;

Fig. 4 is a side elevational view, looking at a second gable; and

Fig. 5 is a side elevational view, looking at the third gable.

The characteristic features of my design are shown in full lines.

I claim:

The ornamental design for a building, substantially as shown and described.

ANTON KRATOCHVIL.
